(57) **CLAIM**

The ornamental design for a golf club grip, as shown and described.

DESCRIPTION

FIG. 1 is a perspective view of a golf club grip showing our new design;

FIG. 2 is a right side view thereof;

FIG. 3 is a left side view thereof;

FIG. 4 is a back side view thereof;

FIG. 5 is a front side view thereof;

FIG. 6 is a bottom plan thereof; and,

FIG. 7 is a top view thereof.

The broken lines shown are included for the purpose of illustrating unclaimed portions of the subject matter and form no part of the claimed design.

1 Claim, 4 Drawing Sheets
